CLAIM

The ornamental design for an externally mounted plenum for limited slip differential, as shown and described.

DESCRIPTION

FIG. 1 is a front perspective view of an externally mounted plenum for limited slip differential showing the new design. FIG. 2 is a first side elevation view of the externally mounted plenum for limited slip differential.

FIG. 3 is a second side elevation view of the externally mounted plenum for limited slip differential.

FIG. 4 is a front elevation view of the externally mounted plenum for limited slip differential.

FIG. 5 is a top plan view of the externally mounted plenum for limited slip differential.

FIG. 6 is a bottom plan view of the externally mounted plenum for limited slip differential; and,

FIG. 7 is a rear elevation view of the externally mounted plenum for limited slip differential.
